UNITED STATES PATENT OFFICE.

THADDEUS F. BAILY, OF ALLIANCE, OHIO.

SHAFT-TYPE ELECTRIC FURNACE.

Application filed July 19, 1927. Serial No. 206,865.

The invention relates to furnaces of the shaft type, and more particularly to electric furnaces of this general character in which an electrode is located at each end of the furnace, the charge forming a resistor between the electrodes to maintain the desired temperature within the furnace.

The object of the improvement is to provide a shaft type furnace arranged to be charged at its upper end, the charge passing downward through the furnace to be discharged at the lower end, an electrode being located at each end of the furnace and the charge normally filling the entire furnace between the electrodes, forming a resistance through the charge between the electrodes for developing heat within the furnace; means being provided whereby when working charges which in the re-action create a combustible gas, this gas may be burned for preheating the charge before it enters the furnace shaft.

The improved apparatus, with slight modification, is adapted for the manufacture of synthetic pig iron, producing flake graphite as a by-product; for producing silicon direct from SiO_2 ; for producing silicon carbide from SiO_2 and carbon; and for producing amorphous graphite from amorphous carbon.

The above and other objects may be attained by providing a vertical shaft type furnace having an electrode at its upper end and an electrode at its lower end, one or both of which electrodes may be in the form of a ring through which the charge passes, the charge which in some cases may be amorphous carbon substantially filling the shaft between the electrodes, whereby resistance is created through the charge to maintain the desired furnace temperature.

Where it is desired to utilize the waste combustible gas from the re-action for pre-heating the charge, this waste gas may be taken off at the top of the shaft and admitted to a preheating chamber, preferably of the inclined rotary type, through which the charge is passed for preheating before entering the shaft.

Various embodiments of the improved furnace are illustrated in the accompanying drawings, in which

Figure 1 is a vertical sectional view through the improved furnace adapted for the manufacture of synthetic pig iron from scrap and so arranged that flake graphite may be produced as a by-product;

Figure 2, a similar view showing an adaptation of the improved furnace for the manufacture of silicon;

Fig. 3, a similar view showing the furnace adapted for the manufacture of silicon carbide, and

Fig. 4, a vertical sectional view through the furnace adapted for the production of amorphous graphite from amorphous carbon.

Similar numerals refer to similar parts throughout the drawings.

Referring first to the form of the furnace illustrated in Fig. 1, it will be noted that a shaft type furnace is provided adapted to be charged with amorphous carbon such as coke, the scrap being melted in the top of the shaft and passed downward through the coke and being discharged at the lower end of the shaft into suitable molds for casting pig iron, or into a ladle or the like.

By superheating the molten iron, as it passes through the coke, a surplus amount of carbon will be picked up by the iron which, upon cooling, will be thrown off from the bath, in the form of flake graphite, thus producing the graphite as a by-product of the operation.

In this form of the furnace, the apparatus comprises broadly the melting chamber 1 communicating with the upper end of the shaft 2, the lower end of which communicates with the crucible 3.

The melting chamber may comprise the steel shell 4, supported in any suitable manner as by the structure including the I-beams 5 and standards 6.

This melting chamber may be lined with any suitable material, such as fire brick, shown at 7, and provided in its lower portion with the lining 8, of carbon or the like.

The roof 9, of the melting chamber, may also be lined with fire brick, or the like, indicated at 10, and one or more electrodes 11 may be supported from the shell by brackets, such as shown at 12, and arranged to be vertically adjusted, within the melting

chamber, as by the apparatus indicated generally at 13.

The roof has the central charging opening 14 through which scrap iron or other material to be melted may be continuously or intermittently charged into the melting chamber.

The shaft 2 is located beneath and communicates at its upper end with the lower open end of the melting chamber. This shaft comprises the steel shell 15, which may be lined with silicon carbide, or the like, as shown at 16.

The lower end of the shaft opens into the crucible 3, which may be provided with the steel shell 17, mounted upon the I-beams 18, supported from the uprights 6, and is provided with a lining 18^a, of fire brick or the like, and preferably has the discharge spout 19 at its lower end.

An electrode 20 extends up through the bottom of the crucible and is connected, as by the cable 21, with the three-phase circuit in which the upper electrodes 11 are also located.

In operating the furnace, to produce pig iron, the crucible, shaft and melting chamber are filled with amorphous carbon, which may be in the form of lump coke as indicated at 22, to a point slightly spaced below the upper electrodes 11.

Scrap iron is then charged through the charging opening 14 of the roof, upon the top of the bed of coke, and an arc will be produced between the scrap iron and the upper electrodes 11, rapidly melting the scrap down. As the iron melts it will trickle down through the coke and into the crucible.

The entire mass of coke, together with the scrap iron which is charged into the furnace, will form a resistor between the upper and lower electrodes, maintaining a high temperature throughout the stack and crucible as well as in the melting chamber, thus keeping the metal molten as it passes downward through the furnace, after being melted by the arc in the melting chamber.

When the metal has started to melt, the charging of scrap in the melting chamber will be substantially continuous and a continuous stream of molten iron will pour from the discharge spout.

A ladle or the like may be provided below the spout 19 to receive the stream of molten metal, or the molten stream may be run directly into pig molds.

If it is desired to produce graphite, as a by-product of the iron, it is only necessary to run the furnace at a higher temperature, thus causing the molten iron to absorb a larger percent of carbon from the coke charge in the furnace.

The molten stream of iron would then be run from the discharge spout 19 into a

ladle or the like and in cooling, the surplus carbon would be thrown out of the bath, in the form of flake graphite.

To compensate for the loss of carbon absorbed in the molten iron, carbon may be charged with the scrap iron from time to time.

In Fig. 2 is illustrated an adaption of the improved furnace for producing silicon from SiO_2 and carbon, or for producing ferro-silicon from silica, carbon and ore or scrap iron.

In this form of the invention the apparatus comprises generally the rotary preheating furnace 25, the vertical resistance shaft 26, and a hood 27 forming a communication between the upper end of the shaft and the discharge end of the rotary furnace for conveying waste combustible gases from the shaft into the preheating furnace.

The rotary furnace comprises a cylindrical shell 28, which may be lined with beauxite brick, as indicated at 29, and is mounted in a position slightly inclined from the horizontal as illustrated, being preferably provided with the rings 30 which rest upon the rollers 31.

A ring gear 32 may be provided around the shell and meshed with a pinion 33, driven from any suitable source of power, to continuously rotate the preheating furnace at the desired speed.

A feed hopper 34 is supported upon any suitable structure as indicated at 35, and extends into the upper end of the rotary furnace.

When making silicon, SiO_2 and carbon, in the proper proportions may be charged into the hopper 34, the carbon preferably being in the form of coke in fairly large lumps.

If desired, the SiO_2 may be charged into the hopper while the coke may be charged directly into the upper end of the shaft 26 by means of a bell hopper or the like.

When making ferro-silicon, either scrap iron or iron ore, in the desired proportions, may be charged into the hopper 34 with the SiO_2 and carbon.

The shaft 26 comprises the vertical cylindrical steel shell 37, which may be lined with beauxite brick, or the like, indicated at 38. This shell is supported above the floor level, as by the uprights 39, the upper end of the shell being supported by the structure, indicated generally at 40, which also supports the rotary furnace.

At the upper end of the shaft is located an annular carbon electrode 41, the clamp 42 of which connects the same to a cable 43 leading to one side of an electric circuit. This clamp is preferably water cooled, as indicated at 44, in order to compensate for the high temperature at which the electrode is necessarily operated.

An electrode 45 is located up through the

lower end of the shaft and may be surrounded by the carbon ring 46, forming, with the electrode, the bottom of the interior of the shaft.

5 This lower electrode is provided with a clamp 47 for the purpose of connecting the same to a cable 48 located in the other side of the electric circuit above referred to. A discharge spout 49 is provided in the lower 10 end of the shaft.

In operating the furnace, the interior of the shaft is first filled with amorphous carbon, which may be in the form of lumps of coke, as indicated at 50, this coke extending 15 from the lower electrode up through the upper electrode, thus forming a resistance element whereby the interior of the shaft may be maintained at high temperature.

At the upper end of the shaft the hood 27 20 is provided, the lower end of the rotary furnace extending into said hood. This hood may comprise the steel shell 51, having a lining 52 of any suitable insulation material. A pipe 53 may be located through the 25 hood 27 and into the lower open end of the rotary furnace for furnishing air for combustion.

In operating the furnace to produce silicon, the rotary furnace may be charged with 30 SiO_2 and carbon as above described and the same may be initially melted by inserting a gas or oil burner into the rotary furnace.

The melted silica, with the coke floating 35 thereon, will be continuously poured from the lower end of the rotary furnace through the annular electrode 41 and into the mass of coke 50 in the shaft furnace.

This mass of coke in the shaft furnace 40 will be heated by forming a resistance between the electrodes and will be maintained in an incandescent state, permitting the molten silica to trickle down through the same.

This molten silica will absorb carbon from 45 the coke charge and will pass from the discharge spout 49 in a more or less continuous stream in the form of silicon.

If it is desired to produce ferro-silicon, either ore or scrap iron in suitable quantities 50 may be charged in the rotary furnace with the SiO_2 and carbon, the molten mass passing down through the coke as above described and being discharged from the spout 49.

55 A considerable amount of combustible gas will be generated by the re-action in the electric shaft furnace and this gas will pass upward through the hood and into the rotary furnace, mixing with the air from the pipe 53 and being burned to melt the material in the rotary furnace, thus making it unnecessary to continue the gas or oil burner after the reaction in the electric furnace has started.

60 An adaptation of the improved furnace to

the production of silicon carbide is illustrated in Fig. 3. In this form of the furnace the rotary furnace 25, hood 27 and feed hopper 34 may be all as above described and as illustrated in Fig. 2.

70 The shaft 26^a comprises the metal shell 37^a, having a suitable refractory lining 38^a within which is located a carbon tube 38^b, it being preferable to locate a layer of lamp black between the carbon tube and the refractory lining.

75 An annular electrode 41^a is located at the upper end of the shaft and contacts with the upper end of the carbon tube, and a similar annular electrode 45^a is located at the lower end of the shaft and contacts with the lower end of the carbon tube, whereby at least a portion of the current passes through the carbon tube between the electrodes, producing a resistance. Each of the electrodes is 80 connected by a cable 53^a to an electric circuit.

85 In operating the furnace to produce silicon carbide, SiO_2 and carbon, preferably in the form of crushed coke, would be charged 90 in the rotary preheating furnace in about the proportions of one to three.

95 This mixture may be initially heated to about 3000° F. to 3200° F. in the rotary furnace either by inserting a gas or oil burner or it may be initially heated by operating the electric shaft furnace.

100 This mixture of preheated SiO_2 and carbon will be continuously fed from the rotary furnace into the shaft where it will be subjected to approximately 3600° F.

105 The mass will form a more or less solid core which will slowly feed downward within the carbon tube, a portion at least of the current passing through this mass which becomes an electric resistance element.

110 This action will continue until the lower end of the core passes down through the lower annular electrode 45^a and protrudes below the bottom of the shaft, in the form of a core of silicon carbide which may be broken off from time to time and removed in order to not interfere with the continuous process.

115 In this case, as well as in the furnace for the production of silicon, the combustible gases generated by the re-action in the electric furnace will pass up through the hood and into the rotary furnace where they will be burned for preheating.

120 In Fig. 4 is illustrated a modification of the furnace best adapted for the production of amorphous graphite from amorphous carbon. The shaft comprises the metal shell 55 lined with silicon carbide or the like as shown at 56.

125 This shaft is open at its upper and lower ends both and provided with the upper and lower annular electrodes 57 and 58 respectively, located at opposite ends of the shaft.

These electrodes are connected, as by the cables 59, to an electric circuit whereby the coke charge shown generally at 60 when entirely filling the shaft will act as a resistance element carrying the current between the electrodes.

5 A rotary discharge hearth 61, preferably of substantially conical shape as illustrated, is located at the lower open end of the shaft 10 and may be rotated in any suitable manner as by the gear 62 and pinion 63.

10 In operating the furnace to produce amorphous graphite, the shaft is filled with amorphous carbon preferably in the form of finely pressed coke.

15 As this mass of coke contacts with both of the electrodes, the coke will form a resistor between the electrodes, being maintained in an incandescent condition and preferably at 20 a temperature of from 3600 to 5000 degrees F.

25 New coke is continually charged in the upper open end of the shaft while the amorphous graphite produced by the action of the furnace will be continuously fed out of the lower end of the shaft by means of the rotary hearth.

From the above it will be seen that in each instance a vertical shaft furnace is provided 30 with electrodes at opposite ends of the shaft, means being provided for charging the shaft at its upper end and discharging at the lower end thereof, the charge contacting with both electrodes and forming a resistance element for producing the desired temperature 35 in the furnace.

40 It should be understood that where the shaft is referred to throughout the specification and claims, this shaft need not be of the same height or proportion as illustrated in the drawings but need only be of sufficient size to accommodate a proper amount of carbonaceous material to produce the results as described in the specification.

45 I claim:

1. A shaft type resistance furnace having an electrode at each end and a loose carbonaceous resistor within the furnace extending from one electrode to the other and means for melting a charge of material and 50 passing the molten material downward through the carbonaceous resistor.

55 2. A shaft type resistance furnace having an electrode at each end and a loose carbonaceous material within the furnace adapted to carry current between the electrodes and means for melting a charge of material and passing the molten material downward through the carbonaceous resistor.

3. A shaft type resistance furnace having an electrode at each end, a loose carbonaceous 60 resistor within the furnace extending from one electrode to the other and means for operating the upper portion of the furnace as an arc furnace and the lower portion as a resistance furnace for melting material in the 65 upper portion of the furnace and passing the molten material downward through the carbonaceous resistor.

4. A furnace comprising an arc type melting chamber and a vertical resistance type 70 electrically heated shaft below and communicating therewith, the shaft containing loose carbonaceous resistance material through which material melted in the melting chamber is adapted to pass.

75 5. A shaft type resistance furnace having an electrode at each end, a loose carbonaceous resistance material within the furnace extending from one electrode to the other, a charging opening at the top of the furnace 80 and a discharge opening at the bottom whereby material may be melted and continuously fed downward through the carbonaceous resistance material.

6. In combination, an arc type melting 85 furnace, and a resistance type reduction furnace communicating at its upper end with the lower end of the arc furnace and having a loose carbonaceous resistor through which material melted in the melting furnace is 90 passed.

7. A shaft type resistance furnace having an electrode at each end and a loose carbonaceous resistor between the electrode and means for operating the upper portion of 95 the furnace as an arc furnace and the lower portion as a resistance furnace for melting material in the upper portion of the furnace and passing the molten material downward through the carbonaceous resistor.

100 8. A shaft type furnace having an electrode at each end, a loose carbonaceous resistor within the furnace between the electrodes and means for melting a charge of material at the upper portion of the furnace 105 and passing the molten charge downward through the carbonaceous resistor.

9. A furnace containing a loose carbonaceous resistor, means for melting material and passing it downward through the carbonaceous resistor and means for passing current through the resistor in the same path as the molten material.

110 In testimony that I claim the above, I have hereunto subscribed my name.

THADDEUS F. BAILY.
